J. N. PAUL

AUTOMATIC TRAIN CONTROL SYSTEM

Original Filed Nov. 20. 1919

FIG. 1.

FIG. 2.

Patented Feb. 10, 1925.

1,526,084

UNITED STATES PATENT OFFICE.

JOSEPH N. PAUL, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN-CONTROL SYSTEM.

Application filed November 20, 1919, Serial No. 339,398. Renewed December 30, 1924.

To all whom it may concern:

Be it known that I, JOSEPH N. PAUL, a citizen of the United States, and resident of the city of Rochester, in the county of Monroe and State of New York, have invented a new and useful Automatic Train-Control System, of which the following is a specification.

This invention relates to automatic train control systems for railroads, and more particularly to the means employed in such systems for transmitting controlling impulses or influences from the trackway to locomotives, motor cars, or other railway vehicles moving thereon.

On account of exposure to weather, the problems of clearance, and other reasons, it is desirable that the impulse transmitting means for train control systems should operate inductively; that is, without any physical contact between parts along the track and parts on the moving vehicles. In one type of such an inductive system, and the type to which my present invention more particularly relates, the cautionary or stopping impulse is due to the presence of iron yokes or cores along the track. Other masses of iron, such as the track rails at crossings, crossovers and the like, have the tendency to produce the same stopping effect, and if the equipment on the vehicle is too sensitive, improper operation will be produced by such masses of iron. On the other hand, variations in airgap between the car-carried element and the track element, which are bound to occur in practice, changes in the voltage of the battery on the car (which is usually a storage battery), and other variable factors, impose in practice a working limit to the sensitiveness of the car equipment, in order that the safe and reliable operation may be obtained. Thus, if the equipment is designed and adjusted for safe and reliable operation under the worst conditions of airgap, battery voltage and the like, it is found that the car equipment may be so sensitive as to be sometimes improperly operated at crossings and the like, when the best conditions of airgap, battery voltage, etc., exist. Adjustments for the airgap, battery voltage, and the like may be provided, if desired, to take care of this condition; but I consider it undesirable to depend upon such adjustments, since the requisite adjustment

necessary to make the system safe may not be made sometime for some reason or another.

In view of these considerations, one of the principal objects of my present invention is to provide an improved car equipment which will be influenced to a very small degree by track rails at crossings, and like magnetic bodies along the track, without being any less sensitive to the effect of a regular track element, so that the car equipment may be designed and adjusted so as to operate safely and reliably through the entire range of variations in airgap, battery voltage, or the like, without being susceptible to improper and false operations by the track rails at crossings and the like, and therefore may be permanently fixed on the car without any provisions for adjustment.

Other more specific objects of my invention will be in part obvious and in part pointed out hereinafter during the detailed description of the invention.

In describing my invention in detail I will refer to the accompanying drawing, in which like reference characters refer to corresponding parts in the several views, and in which—

Fig. 1 shows diagrammatically one arrangement of trackway apparatus and circuits embodying the invention;

Fig. 2 illustrates in a diagrammatic and simplified manner the construction and arrangement of the parts and circuits constituting the car equipment, together with the track element forming part of the track equipment; and

Fig. 3 illustrates a modified arrangement of the car equipment.

Referring first to the track equipment shown in Fig. 1, my invention includes track elements T which are automatically governed in accordance with traffic conditions. Various arrangements of trackway circuits for governing these track elements T may be employed; and it should be understood that the circuits illustrated in Fig. 1 are merely typical. The track rails 1 of the railroad track are divided by insulated joints 2 into blocks in the usual way, one block I with the adjacent ends of two other blocks H and J being shown. The parts and circuits associated with the various blocks are the same, and for convenience

will be given like reference characters, with distinctive exponents. Each of the blocks is provided with a track battery 3 and a track relay 4, the same as in ordinary block signal systems. My invention may be used with or without the usual fixed signals, depending upon the type of train control apparatus; and I have illustrated such fixed signals S conventionally; without attempting to illustrate their well known control circuits and devices.

The trackway element T of my invention in general comprises a magnetic yoke or core and associated coils, and is adapted to influence by electro-magnetic induction a cooperating element on a passing vehicle. In the construction illustrated, the trackway element T comprises a U-shaped core or yoke 5 provided with pole pieces 6, and having coils 7 on its legs which are either oppositely wound or in the same direction with different number of turns. These trackway elements T are intended to transmit controlling influences or impulses to a passing train at one or more control points in each block, in accordance with traffic conditions in the next block in advance, or also in the corresponding block, depending upon the type of train control apparatus employed. In the trackway equipment shown in Fig. 1, a trackway element T is located at the entrance to each block, a short distance in the rear of the insulated joints 2, the normal direction of traffic being from left to right, as indicated by the arrow. The coils 7 of each trackway element T are connected in series in a normally closed circuit including the front contact of a line relay 8. In the arrangement illustrated, the controlling circuit for the line relay 8 includes a front contact of the track relay 4 of the corresponding block and a front contact of the track relay 4 of the next block in advance, so that the coils 7 of the trackway element T at the entrance to each block are in closed circuit under clear traffic conditions, but are open-circuited when either the corresponding block or the next block in advance is occupied. The trackway elements T may be located crosswise of the track between the track rails (as shown in Fig. 1), or lengthwise, or outside of either track rail, as preferred. I prefer in practice to have the upper faces of the pole pieces 6 of the trackway element T as high as clearances on the particular railroad equipped will permit; and in some instances I consider it desirable to locate the trackway elements outside of the track rails, since there is more vertical clearance space ordinarily available outside of track rails than between them. It should be understood that other arrangements and constructions of trackway ele-

ments may be employed without departing from the essential features of my invention.

The car-carried or engine element L comprises in general a magnetic yoke or core Y having three legs 9, 10 and 11, each provided with the usual pole pieces, and each having a coil thereon, as the coils 12, 13 and 14 respectively. It may be explained here that the distance between the legs 9-10-11, and also the other dimensions of the yoke Y should be modified in practice to provide the most efficient arrangement. Obviously, the cross-section of the legs and their back yokes is preferably made as small as the flux density will permit so as to keep down the size and weight of the yoke Y. Also, the distance between the legs should preferably be as short as possible, the limitation being that the greater part of the flux should tend to pass down through the track element through the two intervening air-gaps, rather than leak from the leg 9 to the leg 10. Thus, while the track element shown in Fig. 1 is nearly as wide as the track gauge, the distance between the outside legs 9 and 11 of the car element may be made less than the track gauge in most cases, and the track element is then located at one side of the center line of the track so as to come under the legs 9 and 10. The coils 13 and 14 on two of the legs 10 and 11 are conveniently termed the secondary or receiving coils. The coil 13 is the active or working secondary coil, and the coil 14 is the balancing or neutralizing secondary coil. These coils 13 and 14 are wound oppositely with substantially the same number of turns. The relative direction in which the turns of these coils 13 and 14 actually pass around the legs 10 and 11, starting from the same end, may be the same or opposite, depending on how these coils are connected together, that is, end to end, or beginning to end. In any case, however, the coils 13 and 14 are so wound and connected together that the electro-motive forces induced therein by a change in the flux from the field coil 12 passing through the legs 10 and 11 in the same direction, either up or down, will oppose each other; and it is this arrangement which is understood by the use of the expression oppositely wound. The other coil 12 is preferably wound oppositely to the coil 13, or in the same direction with a different number of turns. The engine element L is supported in any suitable manner from the frame of the locomotive or other vehicle, and is preferably non-adjustably secured thereto in such a position that its pole pieces 12 and 13 pass directly over pole pieces 6 of the track element T, as shown in Fig. 2. In connection with my system I employ an amplifying

and detecting relay of the thermionic or vacuum bulb type, commonly known as an audion. This audion, being well known, has been illustrated conventionally, and 5 comprises a filament F, a grid G and a plate P. The filament F is normally heated to incandescence by current from a battery A. The grid circuit includes in series the two secondary coils 13 and 14 and 10 a battery C. The plate circuit includes a control relay R and batteries B and C. The control relay R is preferably a tractive relay provided with a large number of turns so as to be operable on small currents, 15 and with a laminated core, so as to be quick-acting.

The control relay R may govern the operation of any suitable form of train control apparatus or device. Since the particular type of train control apparatus forms no part of my invention, I have illustrated such device K conventionally as an electro-pneumatic valve, which may vent the train pipe and apply the brakes directly, or govern the operation of any other suitable form 20 of train control means. The train control device K is normally energized when the control relay R is picked up and is de- 25 energized when the said control relay drops.

The coil 12, conveniently termed the field coil, is normally energized by current derived from the three batteries A, B and C. For the purpose of checking the integrity of this energizing circuit for the field coil 30 12, said circuit is taken through the train control device K, the complete circuit being:—commencing at battery A, wire 15, coil 12, wire 16, train control device K, wires 17 and 18, front contact 19 of relay R, wires 40 20 and 21 to battery B. A non-inductive resistance 22 is preferably connected across the front contact 19 of the relay R, so as to reduce the arcing of this contact when it opens, this resistance 22 being, of course, 45 large enough so that the train control device K will not be held up if the front contact 19 is open.

Normally, while the car-carried element L is not passing over a track element T, the 50 control relay R is picked up, and the train control device K energized. The voltages of the batteries A, B and C (which are really three sections of a single battery), together with the windings of the coils 12, 13, 55 14, and the various other parts, are so designed and proportioned that normally sufficient current flows in the plate circuit through the control relay R to maintain its front contact 19 closed. The voltages of the 60 batteries A, B and C will, of course, vary in practice, according to the type and operating characteristics of the audion, and likewise the number of turns and resistance of the coils 12, 13 and 14, and the winding 65 of the control relay and the train control

device K, will vary under different conditions, depending upon the electrical and magnetic characteristics of the track and car-carried element, the air gap, and other factors. One typical arrangement, which I 70 have found satisfactory in practice, consists of battery A, four volts, battery B, 12 volts, battery C, 8 volts. With such an arrangement of batteries, and an audion of the type commonly constructed, I use 3000 turns for 75 the field coil 12, and 18,000 turns for the secondary coils 13 and 14. One type of the control relay R, which I have found satisfactory in practice, consists of a comparatively large number of turns, for example, 80 72,000 turns. The train control device K preferably includes an electromagnet or solenoid having the usual pickup and drop-away characteristics. It should be understood, however, that these specific details 85 of construction above mentioned are susceptible of considerable variation in practice.

The operation is as follows:—Under clear traffic conditions, the coils 7 of the track element T are in a closed circuit of low 90 resistance and when the engine element L passes over this track element, the car equipment is not influenced sufficiently to operate the control relay R. I attribute this to the action of the coils 7 which being in a closed 95 circuit, oppose or choke back the passage of flux through the yoke 5 of the track element T, thereby preventing the change of flux in the yoke Y of the engine element L which occurs under dangerous traffic conditions to 100 be now described.

Under dangerous traffic conditions, the coils 7 of the track element T are open-circuited; so that this track element presents, in effect a dead magnetic loop for the two 105 legs 9 and 10 of the yoke Y and their connecting portion. Thus, as the yoke Y passes over the track element T, the reluctance of the magnetic circuit through the coils 12 and 13 is changed, and the flux 110 through these coils, produced by the current normally flowing in the field coil 12, is likewise changed. It is probable that the change of flux through the active or working secondary coil 13 is largely due to diversion of flux produced by coil 12 from leakage paths around the leg 9 into the leg 10 and through said coil 13; but whether due to such diversion of leakage flux or to a change in the reluctance of the magnetic 120 circuit, it is found that a change of flux through the coil 13 actually occurs. Such a change in flux through the coil 13 acts, in accordance with well known principles, to induce an E. M. F. in this coil. While this 125 induced E. M. F. is theoretically a complete alternating cycle, changing direction as the car element approaches and leaves the track element, it is evident that one or the other halves of the wave of this induced E. M. F. 130

opposes the battery C, and thus lowers the potential of the grid G with respect to the potential at the negative end of the filament F. This likewise reduces the current normally flowing through the plate circuit, due to the well known operating characteristics of the audion; and the parts are so proportioned that said current is thus reduced below the holdup value of the control relay 10 R. Thus, the front contact 19 of the relay R opens, thereby causing the train control device K to operate. As soon as the engine element L passes beyond the influence of the track element T, the normal conditions are 15 re-established, so that the parts may be restored to their normal condition, ready for the next operation. In this connection, stick circuits and manually or automatic operated reset devices may be employed if desired; but since the particular manner in 20 which the stopping impulse, after once received, is utilized to control the train, forms no part of the present invention, the details of this control have not been shown.

25 One important requisite of train control systems is that failure of any of the essential parts likely to break down in practice, should be upon the side of safety. This principle is carried out in my car equipment. The train control device K itself is included in a normally-closed circuit, so that any interruption of this circuit, or failure of the battery therein, results in this device being operated. Likewise, burning out of 30 the filament F or any interruption in the grid or plate circuits causes the relay R to open. The train control device K, being included in the circuit for normally energizing the field coil 12, will be operated if the circuit is broken. In short, I have provided an interlinked series of normally closed or 35 normally energized circuits, the failure of any one of which results in the operation of the train control device, so that any failure 40 of the equipment or circuit connections likely to occur in practice will be upon the side of safety.

From the preceding explanation it will be observed that the operation of the relay R is dependent upon the E. M. F. induced in the working secondary coil 13. This induced E. M. F. in turn depends upon the air gap between the engine element L and the track element T, and the magneto-motive force produced by the current in the field coil 12. This current in the field coil 12 depends upon the battery voltage, and upon the resistance of this coil which varies according to its temperature. Furthermore, 50 with the same value of E. M. F. induced in the secondary coil 13, the margin for the operation of the control relay R depends upon how much this induced E. M. F. reduces the current then flowing through said 55 relay R, that is, upon the temperature of the

filament F, and the amount of current in the plate circuit. Therefore, in the particular type of system shown and described, generally speaking, the worst conditions for safe operation, that is, the least sensitivity of the car equipment, consist of a long airgap, high filament temperature, high current in the plate circuit, corresponding to a high battery voltage, and high resistance of the field coil 12, corresponding to a high 70 temperature. The best conditions for safe operation, that is, the most sensitive condition of the car equipment, may be stated, roughly speaking, to be just the reverse. Considering these variable factors, the airgap in practice will vary from about 2½" 75 minimum to 4" maximum, the engine element L being assumed to be permanently and non-adjustably connected to the engine frame. This minimum airgap exists when 80 the wheels of the car are worn down to their smallest diameter, and the maximum airgap when new wheels are substituted for worn wheels. These limits will, of course, vary somewhat in practice, depending upon the 85 road clearances and the extent to which the wheels are allowed to wear down. The battery voltage will vary from maximum of approximately 2.2 volts per cell, corresponding to a full charge, to 1.8 volts per cell, corresponding to full discharge, assuming that a storage battery of the common type is used. The temperature of the field coil 12 will 90 vary approximately in accordance with variations in the atmospheric temperature, 95 which in turn will vary considerably depending upon the location of the railroad.

With the maximum variation of the factors above noted, it has been found rather difficult to select an equipment which, without some adjustment, will be sensitive enough to operate under the worst conditions, and yet will not be too sensitive to be improperly operated by the track rails at 100 crossings and the like, when the best conditions exist.

My improved system obviates this objection by minimizing the effect of track rails and similar masses of iron along the track. This action is due to the additional leg 11 and the balancing or neutralizing secondary coil 14 thereon. When the engine element L passes over the track rails at a substantially right angled crossing, the resultant change of flux is substantially the same in both the legs 10 and 11, and the E. M. F. induced in the coil 13 is approximately balanced by the opposing E. M. F. induced in the coils 14. This balancing or neutralizing action is most effective when the several pole pieces of the engine element L pass simultaneously over a body of iron, like the track rail of a right angle crossing, and this condition is likewise the one having the greatest tendency to cause an improper 120 125 130

operation of the control relay R. In passing over switches, or rails making an acute angle with the track rails and the like, the coils 13 and 14 are successively influenced, so that the balancing effect is reduced, but these successive influences are sufficiently simultaneous to cause them to oppose each other to a certain extent, and further the influences produced by such angularly disposed rails are of a smaller magnitude than those caused by crossing rails at right angles to the trackway, because the air gap between such rails and the car element is much larger when these two devices are angularly disposed with respect to each other, so that the tendency for a false operation is correspondingly reduced. Thus, the provision of an extra leg 11 and the neutralizing secondary coil 14 takes care of practically all of the bodies of iron likely to be encountered along a railroad track; and in case a body of iron influencing only the two coils 12 and 13 should exist, it is merely necessary to build out an extension at the side of such a body to influence the neutralizing coil 14.

From the foregoing description it will be observed that the car element constitutes in effect two partial magnetic circuits in multiple with the field coil 12 as a source of magneto-motive-force for said partial circuits. One of these partial magnetic circuits is through the legs 9 and 10, and the other through the legs 9 and 11. The track element T provides another partial magnetic circuit on the track cooperating or matching with the one on the car through the legs 9 and 10, and thus, when in the active stopping condition, completes the partial magnetic circuit on the car through the working secondary coil 13, thereby producing a change of flux therein and causing operation of the relay R in the manner described. It will be evident that a track rail of a crossing, cross-over or the like, since it extends cross-wise of the running rails farther than the track element, will complete both of the partial magnetic circuits on the car.

The modified car equipment shown in Fig. 3 is the same as that shown in Fig. 2, except that the field coil 12 is put upon the middle leg 10 of the yoke Y, and the two secondary coils 13 and 14 on the two outer legs 9 and 11 of said yoke. This arrangement has the advantage that the partial magnetic circuits on the car through the two coils 13 and 14 are substantially the same length, so that the E. M. F. induced in said coils 13 and 14 by a track rail more equally oppose each other.

In describing my invention, I have outlined certain specific constructions of the car equipment and track equipment, and explained the principles and mode of operation thereof; but it should be understood that these constructions do not exhaust all of the various embodiments of my invention. It is evident that various types of engine elements and trackway elements may be used, providing these elements cooperate to produce an induced voltage in a coil on the car by electromagnetic induction when it is desired to transmit a stopping impulse, and further that this induced voltage is produced by the presence of a magnetic body along the track.

In order to explain the nature and mode of operation of my present invention, I have shown and described the devices and circuits of a complete system which are disclosed in generic and specific forms in other applications; and I desire to have it understood that my idea of the features of the system herein disclosed and not claimed form the subject-matter of other co-pending applications.

Various modifications and adaptations of the audion and its connections, other than the one illustrated, may be employed; and two or more audions, coupled in cascade may be employed, if desired. Likewise various combinations of battery or other sources of current may be used, providing the appropriate potentials upon the filament, grid and plate of the audion are obtained. In short, the particular constructions illustrated are susceptible of considerable adaptation and modification, and I desire to have it understood, therefore, that these specific embodiments of my invention shown and described are merely illustrations of the idea of means and the functions thereof constituting my invention.

What I claim as new and desire to secure by Letters Patent of the United States, is:—

1. In an automatic train control system, the combination with a track element constituting a partial magnetic circuit when in the stopping condition, of an engine element comprising a three-legged yoke, oppositely wound coils on two legs of said yoke and connected in series, both of said coils being subjected to substantially the same influence when the engine element passes an extraneous magnetic body along the track, only one coil being under the influence of the regular track elements, electro-responsive means on the engine connected to said coils, and a normally energized coil on the third leg.

2. In an automatic train control system, the combination with a track element constituting a partial magnetic circuit when in the stopping condition, of an engine element comprising a three-legged yoke, a normally energized field coil on one leg of said yoke, other oppositely wound coils on the other two legs, said field coil and only one of said

- other coils being subject to the influence of said track element, and electro-responsive means having an operating circuit connected to said oppositely wound coils in series.
3. In an automatic train control system, the combination with a track element constituting a partial magnetic circuit when in the stopping condition, of car-carried equipment comprising a source of magneto-motive force and two oppositely wound coils in magnetic circuit therewith, said track element being arranged to influence one coil but not both, an audion having its plate circuit connected to said coils in series, and electro-responsive means controlled by said audion.
4. In an automatic train control system, the combination with a track element constituting a partial magnetic circuit when in the stopping condition, of a car-carried yoke having legs; a normally energized field coil on one leg; an electrically operable brake control device; a circuit including in series a source of current, said field coil and said brake control device; a secondary coil on a leg of said car-carried yoke; and an electro-responsive device influenced by the E. M. F. induced in the secondary coil for controlling said brake control device.
5. In an automatic train control system, the combination with a control relay on a vehicle, of a three-legged engine element and track element adapted to cooperate through an intervening airgap varying from approximately $2\frac{1}{2}$ to 4 inches for controlling said relay, and means associated with said engine element for preventing operation of the control relay by the track rails at a crossing or the like at any of said airgaps.
6. In a train control system, the combination with a trackway device, a car-carried means adapted to cooperate with said trackway device, said means comprising a flux producing coil, an influence receiving coil magnetically coupled with said flux producing coil, a control relay having normally closed contacts and connected to be responsive to the voltage induced in said influence receiving coil, a normally energized train control device, a source of energy, and a normally energized circuit for said flux producing coil including in series said source, the contacts of said relay and said device.
7. In a system of train control in which controlling influences are produced by a change of reluctance of a magnetic circuit of a car-carried means caused by its passage over a trackway means, said car-carried means comprising a flux producing coil and an influence receiving coil having its stopping operation dependent on the energization of said flux producing coil; a normally energized electro-responsive device adapted when deenergized to cause retardation of the car; a source of current; and a circuit including in series said source, said flux producing coil and said device and governed by voltage changes in said receiving coil.
8. In a system of train control in which controlling impulses are produced by a magnetic cooperation between car-carried means and trackway means, car-carried means comprising a flux producing coil and having its operation dependent on the energization of said coil; an electro-responsive device controlled by said car-carried means and operable upon a predetermined decrease in the current flowing therein to cause retardation of the car; said car-carried means including a normally energized control relay having normally closed contacts; a source of current; and an energizing circuit for said flux producing coil including said device and the contacts of said relay.
9. Car apparatus for an automatic train control system, comprising a control relay having normally closed contacts, an electrically operable train control device having an energizing circuit governed by said contacts, and a shunt around said contacts having a resistance high enough to limit the flow of current through said device below the value required to operate it.
10. In an automatic train control system, car equipment comprising a control relay, an electrically operable brake-setting appliance, a normally energized coil for producing flux to govern the operation of the control relay, an energizing circuit including said coil, the brake control device and a front contact of said relay, and a shunt around the relay contact having a resistance high enough to limit the flow of current through the brake-setting appliance below its operating value.
11. In an automatic train control system, the combination with a train control means on a vehicle, of an audion controlling said means, a normally energized circuit governing said audion, and means responsive to magnetic bodies extending partway across the track but not all of the way for producing a counter electro-motive-force in said circuit.
12. In a system for transmitting controlling impulses from the track to moving vehicles of the type in which a source of flux is carried on the vehicle, and in which the track elements act when in the stopping condition to complete a partial magnetic circuit on the car including said source of flux, the combination with said partial magnetic circuit, of means including an audion and responding to a change of flux in said circuit, and other means influenced by track rails extending crosswise of the running rails for preventing active response of said first-mentioned means to said track rails.
13. In a train control system, brake con-

- trol apparatus on a vehicle, a relay governing said apparatus, an audion controlling the relay, a circuit normally maintaining a potential on the grid of the audion, two oppositely wound coils included in said circuit, and means partly on the track and partly on the car for causing a change of flux in one of said coils but not the other under dangerous traffic conditions, said 5 change in flux inducing a counter electro-motive-force reducing the grid potential and decreasing the current through the relay, a like change in flux being produced in both of said coils when the car passes a rail extending crosswise of the running rails.
14. Car equipment for automatic train control systems comprising a partial magnetic circuit, an audion, two oppositely wound coils associated with said magnetic 10 circuit and connected in series in the grid circuit of the audion, and electro-responsive train governing means controlled by the plate circuit of the audion.
15. Car equipment for automatic train control systems comprising train control apparatus, an audion, a normally energized control relay for governing said apparatus and included in the plate circuit for the audion, and two coils and a core therefor constituting a partial magnetic circuit on the car, said coils being wound and connected together in the grid circuit of the audion so that a change of flux passing through said coils in the same direction induce opposing 25 electro-motive-forces.
16. In a train control system, car equipment comprising train control apparatus, a relay for controlling said apparatus, an impulse element comprising a back yoke having three legs, a normally energized coil 30 on one leg tending to send flux in the same direction in the other legs, a source of current and a circuit for energizing said coil, oppositely wound coils on the other two legs, another circuit for controlling the relay including said oppositely wound coils in series, a track element comprising a magnetic core spanning two legs of said element and having a winding for opposing the passage 35 of flux through the core, and traffic controlled means for opening and closing a circuit of low resistance through said winding.
17. In an automatic train control system, a car equipment comprising a three-legged yoke carried on the car crosswise thereof, train control apparatus, an electro-responsive device governing said apparatus, an energized field coil on one leg of said yoke, separate secondary coils on the other legs, both capable of influencing said electro-responsive device, said device being operated when flux from the field coil through one but not both of the secondary coils is changed and traffic controlled track elements 45 acting when in the active stopping condition to cause a change of flux through one but not both of said secondary coils.
18. In an automatic train control system, the combination on a vehicle, of means for governing the operation of said vehicle by apparatus inductively by a field of flux between the vehicle and track, said means comprising a car-carried element having a yoke provided with only three legs, a normally energized field coil on one leg, a secondary coil on another leg, a track element adapted to provide a partial magnetic circuit between the leg carrying the field coil and the leg carrying the secondary coil, traffic controlled means for opposing the passage of flux through the track element under clear traffic conditions, and means associated with the third leg for preventing operation of the train control apparatus, said last mentioned means being operable when partial magnetic circuits on the track are established between the leg carrying the field coil and both of the other two legs.
19. Car equipment for automatic train control systems, of the type in which controlling impulses are communicated by magnetic cooperation between devices on the trackway and devices on the vehicles moving thereon, comprising a three-legged element having oppositely wound coils on two of its legs, a circuit connecting said coils in series, and automatic train control means responsive to a change in the current in said circuit.
20. Car equipment for automatic train control systems, of the type in which controlling impulses are communicated by magnetic cooperation between devices on the trackway and devices on the vehicles moving thereon, comprising a three-legged element, a normally energized field coil on the middle leg, oppositely wound secondary coils on the other two legs, and train control means governed by the secondary coils acting in series.
21. In an automatic train control system, the combination with a U-shaped track element, of a three-legged car element having two of its legs spaced apart substantially the same distance as the legs of the track element, and having a magnetizing coil on one of said legs, said spacing being greater than twice the air-gap between the track element and the car element, means outlying the partial magnetic circuit on the car formed by said two legs of the car element and completed by the track element for controlling the car, and means responsive to bodies of magnetic material extending crosswise of the track a greater distance than the space between the legs of track element for preventing operation of said means.
22. In an automatic train control system of the type in which a source of magneto-

22. A motive-force is carried on a vehicle and in which the track elements act when in the stopping condition to complete a partial magnetic circuit on the vehicle including 65
said source, the combination with train control means on the car, of means including a thermionic relay and responsive to said track elements but not to rails extending crosswise of the track for controlling said apparatus.
23. In a system of train control in which controlling influences are produced by a change of reluctance of a car-carried partial magnetic circuit including a flux producing coil, means magnetically coupled with said flux producing coil including a control relay, a normally energized electro-responsive device adapted when deenergized to cause a retardation of the car, a source of current; and a circuit including in series said source, said coil and said device, and governed by said control relay. 70
24. In a system of train control in which controlling influences are produced by a change of flux in a car-carried means by a traffic controlled trackway means, said car-carried means comprising a flux producing coil, a train control device, a normally energized circuit magnetically coupled with said coil and adapted when deenergized to 75
actuate said train control device; a source of current; and a circuit including in series said source, said coil and said device, and governed by the car-carried means. 80
25. In a train control system in which influences are transmitted from the trackway to the vehicle inductively; car-carried apparatus comprising a flux producing coil, an influence receiving coil magnetically coupled to said flux producing coil, a control relay in circuit with said influence receiving coil; trackway means comprising an inert body of magnetic material adapted to transmit an influence from said flux producing coil to said receiving coil when passing thereover; a train control device, a source of energy; and a circuit including in series said source, flux producing coil and train control device, and governed by said control relay. 85
26. Car-carried apparatus for train control systems comprising, a flux producing coil, an influence receiving coil magnetically coupled with said flux producing coil, a control relay having normally closed contacts and connected in circuit with said receiving coil, a normally energized train control device, a source of energy, and a normally energized circuit for said flux producing coil including in series said source, the contacts of said relay and said device. 90
27. A train control system, as specified in claim 26, having a discharge resistance shunted across the contacts of the control relay. 95
28. In a train control system, the combination of a trackway divided into blocks by insulating joints; each block having a track circuit provided with a track relay and a source of energy; means at the entrance of each block comprising a signal; and a track element controlled by the track circuit of that block and the next block in advance; and a car-carried equipment comprising a three-legged element having oppositely wound coils on two of its legs and so disposed on the car that one of said two legs and the third leg come into communicating relation with said track element as the car passes thereover. 100
29. In a train control system, the combination of a trackway divided into blocks by insulating joints, each block having a track circuit provided with a track relay and a source of energy, means at the entrance of each block including a track element and a signal, said track element being controlled by a line relay controlled by the track circuit of that block and the track circuit of the next block in advance, and car-carried equipment comprising a three-legged element having oppositely wound coils on two of its legs and a field coil on the third leg and so disposed on the car that one of said two legs and the third leg come into communicating relation with said track element as the car passes thereover. 105
30. In a train control system, the combination with a traffic controlled trackway element, of car-carried means adapted to cooperate with said trackway element, said means comprising a flux producing coil, an influence receiving coil magnetically coupled with said flux producing coil, a control relay having normally closed contacts and connected in circuit with said receiving coil, a normally energized train control device, a source of energy, and a normally energized circuit for said flux producing coil including in series said source, the contacts of said relay and said device. 110
31. Influence communicating means for automatic train control systems comprising a three-legged element of magnetic material, coils on the outside legs of said element, a thermionic amplifier having a grid circuit including said coils, and electro-responsive means for controlling the train governed by said thermionic amplifier. 115
